UNITED STATES PATENT OFFICE.

EDSON E. DESCHANE AND JOSEPH C. LITTLEWOOD, OF MINNEAPOLIS, MINNESOTA.

RADIATOR.

No. 877,987.

Specification of Letters Patent.

Patented Feb. 4, 1908.

Application filed April 9, 1906. Serial No. 310,731.

To all whom it may concern:

Be it known that we, EDSON E. DESCHANE and JOSEPH C. LITTLEWOOD, citizens of the United States, residing at Minneapolis, in the 5 county of Hennepin and State of Minnesota, have invented certain new and useful Improvements in Radiators; and they do hereby declare the following to be a full, clear, and exact description of the invention, such 10 as will enable others skilled in the art to which it appertains to make and use the same.

Our invention has for its object to provide an improved steam or hot water radiator for 15 heating systems, and to this end it consists of the novel devices and combinations of devices hereinafter described and defined in the claims.

As is well known, steam and hot water radiators occupy a very considerable valuable 20 space in the rooms in which they are installed.

One of the principal objects of this invention is to provide a radiator that will not occupy 25 space in a room which may be conveniently used for other purposes. To this end we provide comparatively flat elongated radiators which are of such form and are so located that they occupy substantially the 30 space usually occupied by the wooden baseboard, and which may be given ornamental appearance so as to form an ornamental baseboard, thereby eliminating the use of the usual wooden baseboard.

35 The invention is illustrated in the accompanying drawings wherein like characters indicate like parts throughout the several views.

Referring to the drawings, Figure 1 is a 40 view partly in section and partly in elevation, and with some parts broken away illustrating our invention applied in places usually occupied by wooden baseboards. Fig. 2 is a plan view with some parts broken away showing 45 several connected sections of what we term our improved baseboard radiator. Fig. 3 is a detail in elevation showing one of the radiator sections of the construction illustrated in Figs. 1 and 2. Fig. 4 is a horizontal section taken on the line $x^4 x^4$ of Fig. 3. Fig. 5 is a view corresponding to Fig. 2, but illustrating 50 a slightly modified form of joint between the radiator sections. Fig. 6 is a detail in elevation showing one of the radiator sections of the construction illustrated in Fig. 5,

and Fig. 7 is a horizontal section taken on the line $x^7 x^7$ of Fig. 6.

1 indicates the floor and 2 one of the walls of a room, in which the improved radiator is installed. The radiator sections 3 are preferably of rectangular outline in elevation, and are quite thin and flat in cross section, being formed hollow and preferably provided with horizontal ribs 4 that extend centrally from end to end thereof, and are formed with 60 perforations 5 that permit free communication between the upper and lower chambers of the said radiator sections.

In the construction illustrated in Figs. 1 to 4 inclusive, the contacting ends of the radiator sections are beveled preferably at an angle of forty-five degrees, while in the construction illustrated in Figs. 5 to 7 inclusive the contacting ends of said radiator sections are united by rectangular lapped joints. The 70 radiator sections that lie in the same plane are connected by nutted bolts 6 (preferably three in number at each joint), the said bolts being passed through the overlapping parts of 75 said radiator sections, at the upper, lower and central portions thereof. The radiator sections that are united at the corner of the room are connected preferably by machine screws 7 passed through perforations in one of the sections and screwed into suitable 80 seats in the other section.

In the construction illustrated in Figs. 1, 2, 3 and 4, the horizontally aligned upper and lower chambers of the radiator sections open directly into each other, while in the construction illustrated in Figs. 5 to 7 inclusive, the upper and lower chambers of said sections 85 communicate with each other through ports 5.

The lower edges of the radiator sections 3 are spaced apart from the floor by rest lugs 90 9, and the said sections are preferably formed on the faces which are nearest to the wall with lugs 10, upon which are placed coiled springs 11. These coiled springs 11 react 95 against a part rigid with respect to the wall, 100 which part is preferably a metal plate 12 that is spaced slightly inward from the wall by strips 13, and is provided at its upper edge with an inwardly and downwardly turned deflecting flange 14.

The springs 11 permit slight lateral movements of the radiator sections, to compensate for expansion and contraction, and the lugs 10 should, therefore, terminate slightly short 105 of the plate 12. For the introduction of 110

steam or hot water into one or more of the connected radiator sections a supply pipe 15 is tapped therein; and when the radiator is used in a hot water system suitable return pipe connections should of course also be provided.

To give a finished appearance to the radiator perforated metallic molding strips 16 are applied to the lower portions thereof and extend to the floor; and for the same purpose a perforated metallic molding strip 17 is attached to the upper portion of the radiator, and is extended to the wall above the radiator and above the deflecting flange 14 of the plate 12.

In Fig. 1 the numeral 18 indicates a fresh air inlet pipe which leads from the exterior of the building into the space between the wall and the radiator, and is provided with a valve 19 which, as shown, is adapted to be moved by means of a stem 20 that works upward through suitable bearings in the upper spacing strip 13 and in the upper molding strip 17. As is evident, the air that comes into contact with the exposed inner surface of the radiator will move directly upward, while the air which is heated in the space between the radiator and the wall, or the wall plate 12, will move upward and pass out through the perforations of the upper molding strip 17, while cold air will freely enter through the perforations of the lower molding strip 16. The deflecting flange 14 of the wall plate 12 causes the air to change its course in passing upward, and hence causes the precipitation of any dust or light

particles that tend to move upward with the rising current of hot air. The radiator sections are so formed that they are adapted to be sawed or cut vertically at any of the several points between the several perforations 5 of the intermediate rib 4. Said sections may be cut obliquely, as shown in Figs. 1 to 4 inclusive, by means of a hack saw. Also the central connecting rib 4 serves to give great lateral strength to the side walls of the radiator sections, and thus adapts the said sections, even when made very light in weight, to stand high internal pressure.

The device described is simple, is efficient for the purposes had in view, may be installed at comparatively small cost, and, as already stated, does not take up space within a room which is useful for other purposes.

We claim as our invention:

In a device of the kind described, the combination with a plurality of flat hollow sections united and having communication at their abutting ends, of wall plates spaced apart from said radiator sections and having downturned deflecting flanges, and a perforated molding strip applied to the upper portions of said radiator sections and extended upward and over the deflecting flange of said wall plate, substantially as described.

In testimony whereof we affix our signatures in presence of two witnesses.

EDSON E. DESCHANE,
JOSEPH C. LITTLEWOOD.
